COLLAPSIBLE DISPLAY EASEL

Louis A. Berlin, Detroit, Mich.

Application May 11, 1934, Serial No. 725,109

8 Claims. (Cl. 248—197)

This invention relates to easels and particularly to collapsible easels.

An object of the invention is to provide an easel for display purposes, which may be readily collapsed to a very compact form.

Another object is to provide an improved mechanism for holding the easel legs selectively adjusted, in length.

A further object is to provide a quickly releasable fastening for positively holding the easel laterally extended.

These and various other objects the invention attains by the construction hereinafter described, and illustrated in the accompanying drawing, 15 wherein:

Fig. 1 is a perspective view of the easel, extended and adjusted for use.

Fig. 2 is a rear view of the easel as fully collapsed.

Fig. 3 is a fragmentary perspective view of the connection between the rear leg of the easel and a pair of toggle arms.

Fig. 4 is a sectional detail of one of the legs, showing a spring latch for holding the leg selectively adjusted in length.

Fig. 5 is a fragmentary horizontal section showing the connection of a pair of brace members to the rear leg.

Fig. 6 is a fragmentary vertical section showing 30 the rear leg connection to the easel.

The improved easel comprises a pair of front legs 1, a toggle linkage 2, 3 adapted to hold said legs spaced apart, or permit them to assume close mutual proximity, and a rear leg 4, so pivoted on said

linkage as to either diverge rearwardly from the plane of the front legs or occupy said plane.

The toggle links 2 are pivoted to the upper ends of the legs 1 and are pivotally interconnected by the relatively short cylindrical link 3 on which the

40 leg 4 is mounted. Thus the latter leg rigidly and transversely carries on its upper end a sleeve 5 mounted on the link 3 and adapted for a limited rotation thereon. For limiting such rotation and thus establishing a definite rearward inclination of

45 the leg 4 when the easel is in use, there is formed in the sleeve 5 a short circumferential slot 7, through which projects a screw 8 or the like, rigidly carried by the link 3. When the leg 4 has

50 been swung to a proper rearward inclination, the screw 8 acts as a stop by engaging an end of the slot 7.

To positively latch the links 2 and 3 in their alined positions in which the front legs are held apart, a pair of sleeves 9 are mounted on the links 55 2 and are slidable over the joints between the links

2 and 3 to establish substantial rigidity at said joints.

To the legs 1 may be secured any suitable arrangement for holding a display, of floral or other character, such arrangement, however, necessarily being of a nature to permit collapse of the easel. Thus there is illustrated a lazy-tongs type of rack carried by and in front of the legs 1, said rack comprising two crossed series of metal bars 10, pivotally connected at their crossings, as indicated at 11. Since the vertical extent of such a rack increases with collapse of the rack, it is permissible to fix the rack on the legs 1 at two points thereof, but any other connections to the legs must slide thereon. It is preferred to fix two points on 15 the top portion of the rack on the legs 1 and to slidably engage the lower portion of the rack with said legs. Thus the bolts 12 which pivot the toggle links 2 on the legs 1 serve also to attach the top portion of the rack to the legs, said bolts each 20 further pivotally interconnecting two of the crossed rack bars 10. The bottom portion of the rack is pivoted on a pair of collars 13, freely slideable on the legs 1.

Preferably all three legs are adjustable in 25 length, each comprising two or more telescopically engaged tubular members. For maintaining adjustments the inner member of each leg terminally carries a spring latch arm 14, provided on its free end with a pin 15 yieldably urged by the bias of said arm against the wall of the outer leg member, so as to engage in any of a series of apertures 16 formed at longitudinal intervals in said outer member.

If, for any purpose, it is desirable to impart 35 considerable rigidity to the described easel, when extended for use, it may be further equipped with a pair of brace links 17, having adjacent ends pivoted to a collar 18 slidable on the mid portion of the rear leg and individually pivoted at their 40 other ends upon collars 19, free to turn on the mid-portions of the legs 1, but held from sliding on the latter by set collar 20. Thus when the easel is collapsed, the links 17 may lie between the legs 1 and 4, as appears in Fig. 2.

The described easel is very conveniently portable, because of its light construction and highly compact collapsed form. It is particularly designed for holding floral decorations but is applicable to various other uses.

What I claim is:

1. An easel comprising a pair of front legs, a pair of toggle links connecting said legs, adapted to hold them apart and providing for their movement toward each other, and a rear leg connected 55

- to the links therebetween and pivotal about its connection to the links to assume a position substantially in the plane of the front legs or rearwardly divergent to such plane, and means at 5 said connection limiting pivotal travel of the rear leg.
2. An easel comprising a pair of front legs, a lazy-tongs rack forming a collapsible connection between said legs and engaging each leg at one 10 fixed point and slidably engaging each leg at another point, and a rear leg having a connection at its upper end to the front legs and pivotally movable about said connection to and from the front legs.
- 15 3. An easel comprising a pair of front legs, a collar slidable on each leg, a lazy-tongs rack forming a collapsible connection between said legs, pivoted on each leg at a fixed point thereof and also pivoted on said collars, and a rear leg 20 having a connection at its upper end to the front legs and pivotally movable about said connection to and from the front legs.
4. An easel comprising a pair of front legs, a pair of toggle links each pivoted to one of said 25 legs, a relatively short link pivotally connecting said toggle links, a pair of sleeves slidable on said links to and from a position embracing the joints between the toggle links and short link, whereby the links may be positively held in alignment, 30 and a rear leg angularly movable on the short link from a position substantially between said legs to a position rearwardly divergent to said legs.
5. An easel comprising a pair of front legs, a connection between the upper ends of said legs including a pair of toggle links adapted to hold the legs apart and providing for their movement toward each other, a rear leg carried at its upper 5 end by and between said links, and means for securing the toggle links in an aligned relation.
6. An easel comprising a pair of front legs, a pair of toggle links each pivoted to one of said legs, a relatively short link pivotally connecting 10 said toggle links, a rear leg angularly movable on the short link from a position substantially between said legs to a position rearwardly divergent to said legs, and means to secure said links in aligned relation. 15
7. An easel comprising a pair of front legs, a pair of toggle links each pivoted to one of said legs, a relatively short link pivotally connecting the toggle links, a rear leg, a sleeve rigidly surrounding the rear leg and rotative on said short 20 link, whereby the rear leg may lie substantially between the front legs or diverge rearwardly therefrom, and means to hold the links in alignment.
8. An easel comprising a pair of front legs, a 25 rear leg, upper and lower link means connecting the front and rear legs, both link means providing for movement of the front legs to and from each other, and the lower pair of links providing for forward and rearward travel of the rear leg, 30 and means for securing the upper link means in alignment.
